UNITED STATES PATENT OFFICE.

HENRY J. TILLAR, OF ALMEDA, TEXAS, ASSIGNOR OF ONE-HALF TO T. H. CRAWFORD, OF HARRIS COUNTY, TEXAS.

LIFTING JACK.

Application filed November 26, 1921. Serial No. 518,014.

To all whom it may concern:

Be it known that I, HENRY J. TILLAR, citizen of the United States, residing at Almeda, in the county of Harris and State 5 of Texas, have invented certain new and useful Improvements in a Lifting Jack, of which the following is a specification.

This invention relates to new and useful improvements in a lifting jack.

10 One object of the invention is to provide a jack of the character described specially designed for the purpose of lifting vehicles, such as motor vehicles, but may be used also for general lifting purposes.

15 Another object of the invention is to provide a jack of the character described which is of simple construction and may be cheaply and easily manufactured and quickly and easily applied to the work.

20 With the above and other objects in view the invention has particular relation to certain novel features of construction, operation and arrangement of parts an example of which is given in this specification and 25 illustrated in the accompanying drawings wherein,

Figure 1 is a side view of the jack, and Figure 2 is a front view thereof.

Referring now more particularly to the 30 drawings the numeral 1 designates the base whose under side is preferably made slightly concaved so as to more readily engage with the ground to prevent slippage. Upstanding from the base are the standards 35 2, 2 which are spaced apart. Pivoted between the upper ends of these standards there is the lift lever 3 whose upper end is formed with an arcuate notch 4 and is extended at one side forming the finger 5 adapted to engage underneath the axle 6 of the vehicle. Pivoted to the lower end of the 40 lever 3 there is manual lever 7 by means of which the jack may be manipulated. The hinge connecting said lever is a one way hinge, that is it is foldable upwardly, as

shown in dotted lines in Figure 1 so as to lie between the standards 2, 2, when the jack is not in use, to permit the jack to be folded in compact form so that it may be readily carried in the vehicle. 50

When it is desired to apply the jack to the work the levers are swung outwardly as shown in Figure 1 and the finger 5 is engaged under the axle. The manual lever 7 is then forced downwardly, the hinge 8 being 55 rigid when operated in this direction, and the axle will be elevated and slip around in the arcuate notch 4. The lower end of the lift lever is forced on inwardly between the standards 2, 2 until said lever assumes a 60 vertical position as shown in dotted lines in Figure 1 and the axle will be thus held elevated and the corresponding wheel will be held clear of the ground. It is obvious that the axle may be lowered by pulling the lower 65 end of the lift lever outwardly.

A jack constructed in accordance with the foregoing specification, and the drawings referred to therein, may be easily and effectively applied to, and released from, the 70 work.

What I claim is:

A lifting jack including a base, spaced standards upstanding therefrom, a lifting lever pivoted between the upper ends of 75 said standards, said lever standing vertically between the standards when in active position, a manual lever pivoted to the lower end of the lifting lever by means of a one way hinge connection, said manual lever 80 having a rigid connection with the lifting lever when forced downwardly but pivoting with respect thereto when forced upwardly.

In testimony whereof I have signed my name to this specification in the presence of 85 two subscribing witnesses.

HENRY J. TILLAR.
